Term of patent 14 years

Int. Cl. D31

U.S. Cl. D19—1

FIG. 1 is an end, bottom and side perspective view of a disposable air tray receptacle for encasing a casket for protection during air shipment, showing my new design in assembled position; and

FIG. 2 is a partially exploded side, top and end perspective view thereof, one of the lifting inserts remaining in assembled position.

The fastening straps shown in FIG. 1 have been omitted from FIG. 2 for convenience in illustration.

I claim:

The ornamental design for a disposable air tray receptacle for encasing a casket for protection during air shipment, as shown and described.
